UNITED STATES PATENT OFFICE.

WILLIAM MEYERS, OF LIMA, OHIO, ASSIGNOR OF ONE-HALF TO CHARLES L. ACKERMAN, OF LIMA, OHIO.

WICKLESS OIL BURNER.

Application filed September 1, 1922 Serial No. 585,733.

To all whom it may concern:

Be it known that I, WILLIAM MEYERS, a citizen of the United States, and a resident of Lima, in the county of Allen and State of Ohio, have invented certain new and useful Improvements in Wickless Oil Burners, of which the following is a full, clear, and exact description.

My invention relates to wickless oil burners and one of the objects of the invention is to provide a burner of this character which will produce substantially perfect combustion, thereby eliminating smoke and disagreeable odors.

Another advantage of my burner is that it is rectangular in form whereby a greater heating surface is obtained than in the usual circular burner of the same size.

A further object of the invention is to provide air inlets of the proper size and properly located, to produce the best results.

Still another object of the invention is to so construct the same that drafts of air will have very little if any effect on the burner.

Another advantage of the invention is that the various parts are so constructed that they may be easily and quickly assembled or disassembled.

A further object of the invention resides in the provision of numerous ridges in the combustion chamber thereby materially assisting in a thorough mixing of the gases.

Another advantage of the invention resides in the provision of a fuel feed pipe highly polished on the interior, thereby assuring a constant and steady supply of fuel.

Another object of the invention is to provide a burner of this character which is extremely neat in appearance and highly efficient in operation, and yet is relatively inexpensive in manufacture.

Other objects and advantages of the invention will be apparent to those skilled in the art, from the following detailed description when taken in connection with the accompanying drawings; in which,

Figure 1 is a vertical section through the burner; the fuel feeding apparatus being shown in elevation.

Figure 2 is a plan view of the burner.

Figure 3 is a side view of the burner.

Figure 4 is a horizontal sectional view taken on line 4—4 of Figure 1.

Referring to the drawings more in detail,

numeral 1 indicates the burner base plate, which is rectangular in shape and is provided with apertured spacing and attaching lugs 2 at each corner thereof. A shoulder 3 is provided in the base plate adjacent the edge thereof, and extends entirely around the same. This shoulder 3 is provided for the reception of the burner shell 4, which also is of course rectangular in cross-section and has the walls thereof inclined upwardly, so that it has the shape of a frustum of a pyramid. An asbestos pad 5 is employed between the lower end of the shell and the base plate, and also between the outer wall of the shell and the shoulder 3 of the base plate.

Spaced inwardly from the first-mentioned shoulder 3 is a second shoulder 6, and outwardly of this shoulder is arranged an upwardly extending flange 7. A trough or generator 8 is mounted on the burner plate and is positioned thereon by the shoulder 6, an asbestos mat being positioned between the generator and burner plate, and between the generator and the flange 7. The generator 8 is rectangular in cross-section and the inner wall thereof extends to a slightly greater height than the outer wall.

The combustion chamber, indicated generally by numeral 9, is formed of an inner wall 10 and outer wall 11. Both walls are rectangular in cross-section and each wall is provided with a shoulder at the bottom thereof for engagement with the walls of the generator.

A cover 12 is mounted on the top of the burner shell and the outer wall of the combustion chamber, the cover being provided with lugs on the inner and outer edges for engaging the combustion chamber wall and the burner shell. The burner shell, the outer wall of the combustion chamber, the cover and the burner base plate, define the outer air space 13, air being admitted to the air space through a suitable number of air holes 14.

Mounted on the top of the inner wall of the combustion chamber is a burner top plate 15 which is cast hollow and has downwardly extending lugs 16 for engaging the combustion chamber wall. The top and bottom walls of the burner top plate are provided with small holes 17 to permit the escape of air in case the pressure should become too great. The burner top plate and

the inner wall of the combustion chamber form the inner air space, indicated by numeral 18. A bolt 19 engages at its lower end with a spider 20 formed integral with the 5 burner base plate, and at its upper end it engages the burner top plate. By screwing down on the nuts provided it will be apparent that the burner top plate, the inner wall of the combustion chamber, the generator 10 and the burner base plate, will all be firmly and securely connected.

A pressure plate 21 is mounted over the cover 12, and is spaced therefrom by means of spacing shoulders 22, the pressure plate 15 also being provided with lugs 23 for engaging the burner shell. Numeral 24, Figure 3, indicates the opening between the cover 12 and the pressure plate 21, whereby air is permitted to freely enter the space 20 formed by the two plates. It is to be noted that the inner edge of the cover 12 is spaced inwardly from the inner edge of the pressure plate 21, for reasons to appear hereinafter.

25 Bolts 24, engage the burner base plate and the pressure plate, and by taking up on these bolts the pressure plate, the cover, the outer wall of the combustion chamber, the generator, and the burner shell are all firmly connected.

The inner and outer wall of the generator are provided with small air holes 25, communicating with the inner and outer air chambers respectively. The inner and outer 35 wall of the combustion chamber have numerous ridges 26 formed thereon, and the walls are also provided with a great number of small round holes 27, communicating respectively with the inner and outer air chamber. Adjacent the top of the outer wall of 40 the combustion chamber, are a plurality of air slots 28 for admitting additional air from the outer air chamber.

A fuel feed pipe 29, inclined at the proper 45 angle, leads through the burner shell into the interior of the generator, being attached thereto by screw-threadedly engaging a lug 30 formed on the outer wall of the generator. A sight feed valve 31, of well known construction, is attached to the feed pipe, and a 50 priming cup 32 also communicates with feed pipe.

In operation, the generator is primed and ignited, and when the burner is thoroughly 55 heated the valve 31 is operated to start the feed of fuel, which may be kerosene, gasoline, alcohol, etc., but ordinarily kerosene will be used as fuel. The oil flows through the pipe 29 into the generator, and it should 60 be mentioned here that the interior of the pipe 29 is highly polished, whereby the feed of fuel is maintained constant.

In the generator the oil is vaporized into a grey vapor, and as the vapors pass upwardly from the generator they combine

with air forming a combustible mixture which burns with a blue flame. The air for supporting combustion is supplied in the following manner:

The burner base plate 1 is spaced from 70 the stove plate by spacing lugs 2, and the air passes into the relatively shallow space between the two plates, then through holes 14 into the outer air space, and through the open bottom of the inner combustion wall 75 into the inner air chamber. From the inner and outer air chambers the air passes into the top of the generator through the holes 25, and into the combustion chamber through the holes 27. As the gases 80 pass upwardly through the combustion chamber, the ridges on the walls thereof cause the gases to thoroughly intermingle, thereby greatly assisting in obtaining complete combustion.

85 At the top of the combustion chamber there is a supplementary air supply to assure complete combustion. For this purpose air slots 28 are provided, and also additional air is supplied through the space between the pressure plate 21 and the cover 12, the inner edge of the pressure plate being spaced outwardly from the inner edge of the cover, whereby the additional air is permitted to pass freely upward. Any excessive pressure developed in the inner air chamber will be permitted to escape through the openings 17.

In oil burners it is highly important that 90 air drafts be avoided, and I have accomplished this in my burner by means of the shallow air space between the stove plate and the burner base plate, and between the pressure plate and the cover. By making these spaces shallow and open on all sides, 95 air drafts have practically no effect on the burner.

100 From the foregoing detailed description it will be apparent that I have devised a burner possessing numerous advantages over previously known burners of this type. The burner being rectangular in shape provides a greater heating surface than is the case in a burner of the same size but circular in cross-section; by the particular construction 105 and arrangement of the fuel and air supplying means the burner produces substantially perfect combustion, eliminating smoke and disagreeable odors.

110 It will be understood, of course, that the burners may be made of any size desired, but in increasing the size of the burner the number of the air holes should be increased while the size thereof remains the same.

115 In accordance with the patent statutes I have described what I now believe to be the best embodiment of my invention, but I do not wish to be understood thereby as limiting myself or the scope of my invention, 120 as many modifications may be made without 125

departing from the spirit of the invention, and all such I aim to include in the scope of the appended claims.

What I claim as new and desire to secure by Letters Patent is:

1. An apparatus of the character described including a burner base plate, a burner shell rectangular in cross-section mounted on the base plate, a combustion chamber spaced inwardly from the burner shell, said combustion chamber formed of two spaced walls rectangular in cross-section, an air chamber on each side of the combustion chamber, the walls of the combustion chamber provided with small holes to permit passage of air from the outer and inner air chamber to the combustion chamber. 10
2. An apparatus of the character described including a burner base plate, a burner shell rectangular in cross-section mounted on the base plate, a combustion chamber spaced inwardly from the burner shell, said combustion chamber formed of two spaced walls rectangular in cross-section, an air chamber on each side of the combustion chamber, the walls of the combustion chamber provided with small holes to permit passage of air from the outer and inner air chamber to the combustion chamber, and said walls of the combustion chamber having a waved formation to assist in mixing the gases. 20
3. An apparatus of the character described including a burner base plate, a burner shell rectangular in cross-section mounted on the base plate, said shell having the shape of a frustum of a pyramid; a combustion chamber spaced inwardly from the burner shell, said combustion chamber formed of two spaced walls rectangular in cross-section, the outer wall of the combustion chamber having the shape of a frustum of a pyramid, an air chamber on each side of the combustion chamber, the walls of the combustion chamber provided with small holes to permit passage of air from the outer and inner air chamber to the combustion chamber. 30
4. An apparatus of the character described including a burner base plate, a burner shell mounted on the base plate, a rectangular generator mounted on the base plate, a combustion chamber mounted on the generator, said combustion chamber formed of spaced rectangular walls, an air chamber on each side of the combustion chamber and generator, both walls of the generator and combustion chamber provided with air holes permitting the passage of air from the outer and inner air passages to the generator and combustion chamber, a burner top plate mounted on the top of the inner wall of the combustion chamber, and said top plate being provided with a plurality of holes. 40
5. An apparatus of the character described including a burner base plate, a burner shell mounted on the base plate, a rectangular generator mounted on the base plate, a combustion chamber mounted on the generator, said combustion chamber formed of spaced rectangular walls, an air chamber on each side of the combustion chamber and generator, both walls of the generator and combustion chamber provided with air holes permitting the passage of air from the outer and inner air passages to the generator and combustion chamber, a burner top plate mounted on the top of the inner wall of the combustion chamber, said top plate being provided with a plurality of holes. 50
6. An apparatus of the character described including a burner base plate, a rectangular generator mounted on the base plate, a combustion chamber mounted on the generator, said combustion chamber formed of spaced rectangular walls, an air chamber on each side of the combustion chamber and generator, both walls of the generator and combustion chamber provided with air holes permitting the passage of air from the outer and inner air passages to the generator and combustion chamber, a burner top plate mounted on the top of the inner wall of the combustion chamber, said top plate being provided with a plurality of holes. 60
7. An apparatus of the character described including a burner base plate, a burner shell mounted on the base plate, a generator mounted on the base plate, a combustion chamber mounted on the generator, said combustion chamber formed of spaced perforated walls, an air chamber on each side of the combustion chamber, a cover mounted on the top of the burner shell and the top of the outer wall of the combustion chamber, a pressure plate mounted on top of the cover and slightly spaced therefrom, and bolts extending between the pressure plate and the base plate. 70
8. An apparatus of the character described including a burner base plate, a burner shell mounted on the base plate, a generator mounted on the base plate, a combustion chamber mounted on the generator, said combustion chamber formed of spaced perforated walls, an air chamber on each side of the combustion chamber, a cover mounted on the top of the burner shell and the top of the outer wall of the combustion chamber, a pressure plate mounted on top of the cover and slightly spaced therefrom, bolts extending between the pressure plate and the base plate, a burner top plate mounted on the top of the inner wall of the combustion chamber, and a centrally arranged bolt extending between the burner top plate and the burner base plate. 80

WILLIAM MEYERS.
